INVENTOR
Bismarck Reynolds
BY *M. W. B. Reynolds* ATTORNEY.

UNITED STATES PATENT OFFICE.

BISMARCK REYNOLDS, OF KANSAS CITY, MISSOURI.

WINDOW LOCK.

Application filed November 13, 1922. Serial No. 600,767.

To all whom it may concern:

Be it known that I, BISMARCK REYNOLDS, a citizen of the United States, residing at Kansas City, in the county of Jackson and 5 State of Missouri, have invented certain new and useful Improvements in Window Locks; and I do declare the following to be a full, clear, and exact description of the invention, such as will enable others skilled in 10 the art to which it appertains to make and use the same, reference being had to the accompanying drawings, and to the figures of reference marked thereon, which form a part of this specification.

15 This invention relates to window sash fasteners. The primary object of the invention is to provide a simple, inexpensive and easily applied fastener which can be secured to the top rail of a window sash so that its 20 effective part may normally be out of operative position, but so arranged that it may be easily thrown into operative position to hold the window sash from being raised by unauthorized persons. The device is so 25 applied that the sash to which it is attached may be held closed or it may be held in any adjusted position so that it cannot be raised beyond the point for which it was set.

The novel construction of the invention 30 will be apparent by reference to the following description in connection with the accompanying drawings, in which:

Fig. 1 is a perspective view of the fastener applied, the inoperative position being 35 shown in dotted lines.

Fig. 2 is a detail perspective view of the fastener detached, and

Fig. 3 is a detail perspective view of a slightly modified form of fastener.

40 Referring now to the drawings by numerals of reference:

1 designates the vertical rail of a window frame of ordinary construction in which is slidably secured a sash 2, the sash being 45 balanced by weights on the ends of cords, there being two cords used in the usual way but only one designated 3 is shown.

The fastener as shown consists of a base member 4 having openings 5 and 6 through 50 which fastening devices such as screws 7 and 8 may pass to fasten the base to the top

rail 9 of the sash. Hinged to the base 4 is a tongue 10 having bifurcated ends to provide prongs 11 and 12 adapted to straddle the cord 3. The ends of the prongs 11 and 12 may engage the window frame when the tongue 10 is in the position shown in Fig. 1. Therefore, the sash 2 cannot be raised because the ends of the tongue will engage the sash and prevent any upward movement. If 60 it is desired to raise the sash, the tongue will be thrown over into the position shown in dotted lines in Fig. 1, whereupon the sash can be raised and lowered in the usual way.

In Fig. 3 I have shown the tongue 10 as 65 provided with the prongs 11 and 12, the prongs being tipped by caps or tips 13 and 14 of rubber or other soft material so that the window frame will not be marred by the metallic ends of the prongs. The construction shown in Fig. 3 conforms exactly to that shown in Fig. 2 except for the refinement of placing the caps 13 and 14 on the prongs 11 and 12.

The application of the device may be 75 easily made by introducing the screws 7 and 8 through the openings 5 and 6 and into the top rail 9 of the frame 2. The device will then be ready for use. The angle which the tongue 10 assumes for the best result can 80 readily be determined by the user, but ordinarily the tongue 10 will give the best results if it assumes an angle of about 45 degrees or even slightly less from horizontal. It should fold far enough away from the 85 vertical to prevent liability of slipping when the ends of the prongs 11 and 12 engage the frame 1.

What I claim and desire to secure by Letters-Patent is:

As an article of manufacture, a sash lock comprising two members hinged together, one being a relatively short base member adapted to be positioned on top of the shaft with its free end directed away from the 95 sash cord, the second member being hinged to the first and consisting of a stiff plate having at its free end spaced prongs, the prongs and body portion of the plate being in the same plane.

In testimony whereof I affix my signature.
BISMARCK REYNOLDS.
